(57) **CLAIM**

The ornamental design for a battery charger, as shown and described.

DESCRIPTION

FIG. 1 is a front, left and bottom perspective view of a battery charger, showing my new design;

FIG. 2 is a rear, right and top perspective view thereof;

FIG. 3 is a perspective view thereof, shown in a closed condition;

FIG. 4 is a front view thereof;

FIG. 5 is a rear view thereof;

FIG. 6 is a left side view thereof;

FIG. 7 is a right side view thereof;

FIG. 8 is a top plan view thereof; and,

FIG. 9 is a bottom plan view thereof.

The broken lines shown in the drawings illustrate portions of the battery charger that form no part of the claimed design.
